(57) **CLAIM**

The ornamental design for a display screen with graphical user interface, as shown and described.

DESCRIPTION

FIG. 1 is a first image for a display screen with graphical user interface showing my new design;

FIG. 2 is a second image thereof;

FIG. 3 is a third image thereof; and,

FIG. 4 is a fourth image thereof.

The appearance of the image transitions sequentially between the images shown in FIGS. 1-4. The process or period in which one image transitions to another forms no part of the claimed design.

The broken lines showing of the display screen and portions of the user interface form no part of the claimed design.
